US0D1025496S

(12) **United States Design Patent** (10) **Patent No.:** **US D1,025,496 S**
(45) **Date of Patent:** **** Apr. 30, 2024**

(54) **FACE SHIELD**

(71) Applicant: **Dennis Augusto Malagutti Silva**, Sao Paulo (BR)

(72) Inventor: **Dennis Augusto Malagutti Silva**, Sao Paulo (BR)

(**) Term: **15 Years**

(21) Appl. No.: **29/870,773**

(22) Filed: **Feb. 3, 2023**

(51) **LOC (14) Cl.** **29-02**

(52) **U.S. Cl.**

USPC **D29/110**

(58) **Field of Classification Search**

USPC D29/100, 102, 105, 106, 107, 108, 110, D29/122; D2/878, 880, 881; D24/110.1
